UNITED STATES PATENT OFFICE.

CLARENCE J. VOORHORST, OF PORTLAND, OREGON.

DIVISION-PLATE FOR EGG-CASES.

1,227,224.

Specification of Letters Patent. Patented May 22, 1917.

Application filed January 16, 1914, Serial No. 812,426. Renewed October 25, 1916. Serial No. 127,532.

To all whom it may concern:

Be it known that I, CLARENCE J. VOORHORST, a citizen of the United States, and a resident of Portland, in the county of Multnomah and State of Oregon, have made certain new and useful Improvements in Division-Plates for Egg-Cases, of which the following is a specification.

My present invention is an improvement 10 in division plates for egg cases, and particularly in that character of division plates described and claimed in my Patent No. 847,854 granted March 19, 1907, the object of my present improvements being to so 15 form a plurality of division plates as that each of the upper plates of a series will support its layer of eggs and be in turn supported by the layer of eggs immediately below the same, the eggs being so held as that 20 their proven strength in each layer will support superposed layers thereabove. The principle involved is that of a saddle which rests upon its support and in turn suspends its load by means of its stirrups.

25 In the accompanying drawing which illustrates my present improvements,

Figure 1 is a sectional view taken through several of the superimposed plates with hemispherical pockets and showing eggs 30 held in position within the pockets,

Fig. 2 is a plan view of one of the complete division plates, portions of which are shown in Fig. 1, and

Fig. 3 is a sectional view taken through 35 a pair of the plates with eggs therebetween, showing pockets in the form of hemi-ovoids.

Referring now to these figures it will be seen, that as in my patent above referred to, I provide plates in each of which pockets 40 are projected to both sides of an intermediate plane and in which the curves of all adjacent pockets in all directions, merge on gradual lines with each other.

In the form shown in Figs. 1 and 2 the 45 pockets are hemispherical, as indicated at A, and no portion of the surface of the plate adjacent to its several pockets is formed in a flat plane, being curved in all directions on lines which merge evenly and 50 gradually with the curvature of the pockets, each pocket having a central opening a the surrounding edge of which is preferably reinforced and the function of which is to receive the points of the eggs of a layer 55 therebelow, thus saddling the plate in such

a manner as to take advantage of the maximum and proven strength of the eggs.

In the form shown in Fig. 3 the several pockets B are in the form of hemi-ovoids, the gradual curvature of the plates between 60 their pockets being sacrificed to a certain extent in order that the pockets themselves may more nearly conform to the precise shape of the eggs, these pockets being formed with central apertures b similar to 65 the openings a of pockets A in Figs. 1 and 2, and for the same purpose, openings b having their surrounding edges reinforced.

In Figs. 1 and 2 the reinforcement of 70 the openings or apertures a is shown in the form of edge flanges which are flattened upon the outer surfaces of the pocket walls, while in Fig. 3 these reinforcements 75 are shown in the form of circular crimps spaced slightly from the edges of the apertures and with the material of the plate pressed outwardly, as regards the several pockets. It is obvious, however, that the same result may be obtained by many other means either in the form of supplemental 80 parts or varied formations of the plates themselves.

By the use of this invention which is, in effect, a saddle system of supporting division plates for use in the storage and transportation of uniformly-shaped equilinear objects, I get the greatest rigidity of maintenance in position together with the greatest flexibility and adaptability to individual idiosyncrasies of the sustained load. The 90 density of the pack is also a maximum.

In use in the packing of eggs, the perforated division plate, with suitable backing, supports the first layer of eggs; a second division plate rides on this first layer 95 of eggs and in turn supports a second layer of eggs, each egg projecting through the division-plate through alternate top and bottom openings to the points of contact with the respective eggs involved; the third plate repeats the function of the second, and so on to the completed stack. If the openings through the plate are a little less than the one-fourth height diameter of the eggs involved the packed case will maintain its 100 load with each vertical series slightly separated from its upper and lower neighbor; its adjacent vertical columns at all sides breaking joints with it at their respective one-half-height and the whole being in a 110

condition of continuous saddle support and rider.

After the stack is completed and bound its position will be negligible, the perforated 5 division-plates maintaining the eggs in their positions in their respective saddles.

The plates may be manufactured from any suitable material, the principles applying to the production of expanded metal 10 lath being applicable, or they may be formed by embossing semi-plastic material or by direct production from the stuff-chest of a paper-mill.

In use the advantages include the possibility of storing within any limited space 15 the greatest number of uniform units, their position rigidly maintained with complete isolation one from the other; maximum ventilation; and the lightest possible construction combined with the greatest structural 20 strength.

I claim:—

1. As an improved article of manufacture, a pocketed division plate for use in the 25 storage and transportation of uniformly shaped objects, having its pockets projecting alternately from its opposite faces and having the curvature of its pockets united each with the adjacent pockets by gradual 30 even surfaces which curve in all directions on lines merging with the curvature of the pockets and in which no flat surface meets a curved surface throughout the pocketed area of the plate, the said pockets being 35 provided with central apertures through which the said objects may partially project and by which the plates are saddled on the objects and the latter maintained in a uniform position, and the edges of the said 40 pockets surrounding their said apertures being reinforced, all for the purpose set forth.

Copies of this patent may be obtained for five cents each, by addressing the "Commissioner of Patents.
Washington, D. C."

2. As an improved article of manufacture, a pocketed division plate for use in the storage and transportation of uniformly shaped 45 objects, having its pockets projecting alternately from its opposite faces and having the curvature of its pockets united each with the adjacent pockets by gradual even surfaces which curve in all directions on lines 50 merging with the curvature of the pockets and in which no flat surface meets a curved surface throughout the pocketed area of the plate, the said pockets being provided with central apertures through which the said 55 objects may partially project and by which the plates are saddled on the objects and the latter maintained in a uniform position to support the several objects out of contact with one another.

3. A pocketed division plate having pockets projecting to both sides of an intermediate plane and having each of said pockets provided with a central aperture through which objects held in the pockets 65 may be partially projected in order to saddle the plates and maintain the objects in uniform position out of contact with one another.

4. As an improved article of manufacture, a perforate division plate having oppositely opening pockets and apertures in the bases of the pockets to receive through its opposite faces, objects disposed in the pockets, to project partially through the said apertures, whereby to maintain the objects in uniform position, out of contact with one another, and thus permit of saddling the plates on the objects in a stack.
